UNITED STATES PATENT OFFICE.

HENRY SPENCER BLACKMORE, OF MOUNT VERNON, NEW YORK.

PROCESS OF MAKING CYANIDS.

No. 889,096.

Specification of Letters Patent.

Patented May 26, 1908.

Application filed October 11, 1902. Serial No. 126,928.

To all whom it may concern:

Be it known that I, HENRY SPENCER BLACKMORE, a citizen of the United States, residing at Mount Vernon, in the county of 5 Westchester and State of New York, have invented certain new and useful Improvements in Processes of Making Cyanids; and I do hereby declare the following to be a full, clear, and exact description of the invention, 10 such as will enable others skilled in the art to which it appertains to make and use the same.

The object of my invention is to make cyanids such as potassium or sodium cyanids and consists in deoxidizing a heated, molten, 15 or liquefied oxy-salt or compound of a metal, the cyanid of which is desired, in the presence of nascent carbon and nitrogen.

My invention is particularly adapted to the fixation of free nitrogen, such as may be 20 obtained from the atmosphere, with carbon in the presence of an alkali whereby the formation of cyanids may be readily accomplished directly in a practical and economical manner yielding a product uncontaminated 25 with injurious foreign ingredients, and is based upon the discovery that hydrogen will deoxidize certain metallic oxids or hydroxids in a heated condition in the presence of carbon and nitrogen, together with the fact that 30 carbon or nitrogen in combination with hydrogen may be concurrently liberated by the union of the hydrogen of both with the oxygen of an oxy-metallic salt during the deoxidation of the heated oxy-salt or compound 35 by the action of the hydrogen content, whereby the metal is reduced in the presence of either nascent carbon, nascent nitrogen or both combining therewith to form metallic cyanids.

As an example of the manner in which my 40 process can be carried out on a practical basis I will take, for example, the production of potassium and sodium cyanids from their corresponding hydrates or hydroxids, reference being had to the accompanying drawings 45 which illustrate an apparatus which I have devised for carrying out the same, Figure 1 of which represents a transverse vertical section of the apparatus and Fig. 2 50 a vertical longitudinal section showing the conversion pots or receptacles connected in multiple.

In carrying out my invention on a practical basis I prefer to introduce into the conversion pot or receptacle A, which is lined 55 with a material B such as magnesite not

acted upon by the materials employed or the product produced, through the opening D in the cover or closure E, a mixture of potassium and sodium hydroxids in proportion of 60 one of the former to two of the latter by weight and proceed to fuse the same or reduce it to a molten condition by means of heat generated in the furnace C by any suitable means. I find that the mixture of 65 hydroxids aforementioned, viz., potassium hydroxid and sodium hydroxid fuses at a lower temperature than either *per se* approximately 300° C., and conversion into cyanid is also more readily effected. 70

When the mixture has assumed a molten, liquefied or free circulating condition approximately 300° C., I close the opening D by means of the cover e and then introduce into and through the molten compounds, through 75 the pipe F, controlled by the valve G, a mixture of nitrogen which has been preferably superheated approximately 285° C., and hydrogen carbid, such as petroleum in a fluid condition, the lower end of the pipe F 80 which extends into the molten compounds in the conversion pot or receptacle A, being composed of a material which is not acted upon by the ingredients employed or the products produced, such as magnesite, and 85 the said section being united to the pipe F by means of the union h.

As the mixture of superheated nitrogen and hydrogen carbid, such as petroleum, is introduced into and through the molten or 90 liquefied potassium and sodium hydroxids the hydrogen combines with the oxygen of the hydroxid concurrently releasing an alkali-metal and carbon which in their nascent condition in the presence of nitrogen 95 immediately unite forming an alkali cyanid, the oxygen of the compound which has thus combined with the hydrogen, passing off at the temperature employed in the form of steam. 100

The reaction which takes place may be illustrated by the following chemical formula or equation:

or employing alkali-oxids instead of hydroxids, as follows:

As the process of conversion progresses

more alkali hydroxid may be added from time to time through the opening D whereupon it assumes a molten or liquefied condition by becoming dissolved in or liquefied by 5 the cyanids previously produced, and therefore it can be readily seen that I may convert the oxy-compounds into cyanids either in a molten condition *per se* or liquefied by the action of inert chemical salts by exposing the 10 said molten or liquefied oxy-compounds to the action of a carbid, the electro-positive element or base of which is capable of uniting with the oxygen of the oxy-salt or compound concurrently liberating carbon and the metal, 15 a cyanid of which is desired, in the presence of nitrogen, it being obvious that the temperature to which the reacting ingredients are exposed must be below the temperature at which carbon will deoxidize the oxy-salt 20 or compound employed in the presence of the electro-positive element of the carbid, it being noted that the carbon of the carbid is the electro-negative constituent thereof and this process relates to the deoxidation of the oxy- 25 salt or compound by the action of the electro-positive element of the carbid at a temperature which must naturally be below the point at which the carbon content will combine with the oxygen content of the composition, or, in other words, at a point at which the 30 electro-positive element will deoxidize oxid of carbon and below the point at which carbon will deoxidize an oxid of the electro-positive element of the carbid, otherwise the carbon 35 would be consumed and dissipated by combination with the oxygen of the oxy-compound instead of forming cyanid, simultaneously producing carbonic oxid or carbon dioxide, the presence of which is detrimental, 40 to the process by retarding and precluding, to a large extent, the formation of cyanid.

It goes without saying that if the hydrogen of the deoxidizing compound, instead of the carbon of that compound, unites with the 45 oxygen of the oxy-compound, the chemical affinity of the hydrogen for the said oxygen must be superior. The temperature, therefore, is necessarily such as to enable the hydrogen to combine or that the electro- 50 positive element does combine, for, as elsewhere indicated, hydrogen has the superior affinity at lower temperatures, while carbon has the superior affinity at higher temperatures.

55 It is obvious that the temperature of the reacting ingredients must be maintained, by refrigeration or otherwise, below the temperature at which the base or electro-positive element of the carbid has the superior affinity 60 for oxygen combined in the compound of metal, a cyanid of which is desired, over carbon, which in the case of hydro-carbon, such as petroleum, is approximately 327° C., the same being about the limit at which hydrogen 65 thereof has a superior affinity for the oxygen

combined in a mixture of sodium hydroxid and potassium hydroxid, while employing such hydrocarbons as petroleum, over its carbon content.

I do not desire to confine myself to the employment of hydrogen carbids as reducing agents in the formation of cyanid but reserve the right to employ any other practical metallic carbid which may be adaptable for the purpose, *i. e.*, the electro-positive element of which is capable of abstracting the oxygen from the oxy-salt or compound of the metal, a cyanid of which is desired, it being a well-known and established fact that hydrogen is a metal in a gaseous state or condition at 70 ordinary atmospheric pressure and temperature from a chemical standpoint just the same as the metal mercury exists as a liquid under like conditions. I can also employ any other oxy-compound of the metal, a cyanid 75 of which is desired, either in a molten condition *per se* or dissolved, liquefied, or retained in a molten bath of inert chemical compounds. When the oxy-compound in the conversion pot or receptacle A has been converted into cyanid it may be withdrawn 80 from time to time as desired through the tap-hole H by withdrawing the plug or stopper J by the actuation of the screw-threaded closing device K.

85 It is found advisable to connect the apparatus as shown in Fig. 1 in multiple as shown in Fig. 2 so that any of the hydrogen carbid and nitrogen which may have passed through the first conversion pot or receptacle A without absorption or combination may be converted and united in a second or third similar apparatus as before described. This particularly applies to cases where the material in the first conversion 90 pot or receptacle has been almost entirely converted into cyanid at which time larger quantities of the hydrogen carbid and nitrogen pass off without reaction or combination and it is also advisable to arrange the 95 apparatus in such a manner that the products produced in the first, second, or third removed apparatus may be conveyed by gravity or otherwise toward the first receptacle so that the compounds may be thoroughly converted by the time they are withdrawn as a finished product.

100 I find it of advantage both from economical and practical stand points to add alkali carbonates from time to time to the molten constituents of the conversion pot or receptacle whereby in its liquefied condition in the inert contents of the said receptacle it is as readily converted as the more fusible alkali oxy-compound. I can also introduce the nitrogen in the form of a hydrid instead of free nitrogen together with the hydrogen carbid by which means nitrogen and carbon are both liberated concurrently 105 with the alkali metal by the union of the 110

hydrogen combined with both the nitrogen and carbon with the oxygen of the alkali metal compound, or I can employ any compound capable of producing or releasing 5 free or nascent nitrogen in a form capable of uniting with the nascent metal and carbon to form a cyanid.

I also intend to include as my invention the heating of the ingredients, viz., metallic 10 oxy-salts or compounds, carbid of the character described and nitrogen, to a reacting temperature which may, in some cases, not actually be a molten or liquefied condition at the time of reaction but which later may 15 become molten or liquefied by action of the more fusible cyanid produced.

The compounds herein referred to, designated by the prefix "oxy" to metallic salts or compounds employed for transformation, is intended to include all salts or compounds of metal or metals, cyanid of which is desired, containing oxygen either individually or associated with other non-metallic elements; and the term "metallic carbid" 25 to a compound of solid, liquid or gaseous metal with carbon, be it either a normal carbid, acetylid or other union and is intended to include any mixture or combination of carbids as well as a simple carbid *per se*, the electro-positive element or base of which is capable of abstracting the oxygen from the oxy-salt or compound of the metal, a cyanid of which is desired.

I can also perform the conversion into 35 cyanids of the oxy-salts or compounds of the metal or metals, cyanid of which is desired, by employing inert salts or compounds which may facilitate fusion by dissolving or suspending the same in a state 40 of fusion whereby the transformation into cyanid is also facilitated; and I can expose the compounds to be transformed to a heat capable of fusing it and introduce the nitrogen and carbid of the character described 45 after fusion or during fusion or I can add the same to the fused composition or expose the mixture of oxy-salt or compound, nitrogen and the carbid, to a reacting temperature without departing from the spirit of 50 my invention which consists in deoxidizing an oxy-salt or compound of the metal or metals, a cyanid of which is desired, by action of the electro-positive element or base of a carbid at a reacting temperature 55 whereby the carbon and metal, a cyanid of which is desired, thus concurrently released in the presence of nitrogen, unite therewith to form cyanid.

I am aware that processes have been devised 60 for uniting nitrogen directly and indirectly with carbids of metals, cyanids of which are desired, it being noted that the metal and carbon are united and the formation of cyanid depends on the absorption of 65 the nitrogen, but in these cases the carbids

being fusible only at extremely high temperatures merely admit of superficial action thereby producing contaminated cyanids below fusion, and if heated to fusion preclude the formation of cyanids by being at a temperature above the dissociating point of the cyanid, also in these cases noted, the metal, a cyanid of which is desired, is exposed to the action of nitrogen while it is combined with carbon in the form of a carbid, while in my process I employ carbon in a free nascent condition in the presence of a nascent metal, a cyanid of which is desired, and nitrogen, which nascent condition greatly facilitates the perfect combination and fixation of nitrogen.

I am also aware that processes have been devised whereby alkalies have been mixed with carbon and heated to a point at which the carbon deoxidizes the same, producing alkali-metal and carbon oxid and exposing it to the action of nitrogen or ammonia or both, the high temperature required to reduce the alkali with carbon is found however to be detrimental to the ready formation or production of cyanid, the carbon oxid evolved upon reduction also exerts an injurious influence and retards the formation of the cyanid and the final separation of the cyanid from excess of free carbon is almost impossible. It has also been proposed to mix hydrocarbons with a mixture of oxygen and nitrogen (ordinary air, either alone or with ammonia gas) and heat the same to a temperature at which the free oxygen of this mixture combines with the hydrogen contents of the hydrocarbon liberating carbon which is retained in suspension in the nitrogen in the form of infinitesimal particles (such as smoke) and then conveying this mixture of nitrogen and free finely subdivided carbon into the presence of an alkali which is heated to a temperature at which the carbon introduced will deoxidize the alkali leaving the excess of carbon and nitrogen to unite with the alkali metal thus reduced to form cyanid with the same. It can be seen, however, that the carbon in this case is not exposed in a nascent state, to the action of nascent alkali-metal in the presence of nitrogen as employed in my process, and the same difficulties met with in reference to high temperature and carbon oxid, still exist; it has also been proposed to decompose alkalies by the action of metallic carbids, such as calcium carbid heated to a temperature at which both the carbon and calcium abstract the oxygen from the alkali liberating the alkali-metal in the form of vapor associated with the gaseous products of deoxidation, carbon oxid and nitrogen, then exposing ferrocyanids, such as potassium ferrocyanid, to the action of this alkali-metal vapor, thereby displacing iron from the ferrocyanid and leaving alkali cyanid free from iron; it has also been proposed to first heat

hydrogen carbid, such as acetylene, and nitrogen by themselves or in the presence of ammonia to a temperature at which the nitrogen is absorbed by the hydrogen carbid producing hydrocyanic acid, or cyanogen in case ordinary air is employed in place of nitrogen, and then conveying the cyanogen (nitrogen carbid) or hydrocyanic acid in contact with alkali, either in a heated or molten condition or in solution in water whereby the hydrocyanic acid combines with the alkali secondarily forming a cyanid of the alkali-metal content or cyanogen which combines with the alkali forming cyanid and cyanate of the alkali-metal content. It is seen, however, in this process that the hydrocyanic acid or cyanogen is first formed and caused to react with the alkali thereafter secondarily and independently producing cyanid, while, in my process, no free hydrocyanic acid or cyanogen is produced but the formation of metallic cyanid is accomplished directly by the union of nascent metal and nascent carbon in the presence of nitrogen. The formation of hydrogen carbid (acetylene) to be employed as aforesaid, was produced either by the decomposition of metallic carbid with steam or aqueous moisture or by the so-called cracking or dissociating of heavy hydrocarbons at high temperatures and the union of nitrogen with the hydrogen carbid (acetylene), forming hydrocyanic acid, was a mere absorption of nitrogen by the hydrogen carbid content.

The carbids which I prefer to employ in the formation of cyanids, viz., hydrogen carbids (petroleum) are those which are not affected or decomposed by the action of moisture at ordinary temperatures and the electro-positive element or base of which is capable of abstracting oxygen from the oxy-salts or compounds of the metal, a cyanid of which is desired, with the simultaneous re-release of the carbon of the carbid, which released elements unite with the nitrogen present forming cyanid. It is also preferable to employ an excess of vaporized petroleum circulating through the molten alkali with the nitrogen so that the water vapor (H_2O), liberated during deoxidation of the alkali (KOH — $NaOH$) with the hydrogen content of the petroleum is rapidly carried out and away from the cyanid to prevent formation of ammonia and consequent loss of cyanid.

By employing molten alkali containing iron oxid, alkali ferrite, or similar iron compound, alkali ferro-cyanid can be produced. I can also use other hydrogen carbids (hydrocarbons) such as acetylene instead of petroleum without departing from the spirit of my invention. I can also introduce the nitrogen into and through the oxy-salt of the metal, a cyanid of which is desired, in combination with carbon and hydrogen, such

as pyridin (C_6H_5N) in a fluid condition instead of nitrogen hydrid as aforesaid while the ingredients are heated to a reacting temperature, in which case the union of the hydrogen with the oxygen of the oxy-compound liberates carbon and nitrogen from the pyridin or similar nitro-hydrocarbon which nascent nitrogen and carbon unite directly with the nascent metal concurrently liberated forming a cyanid therewith. 75

The spirit of my invention, therefore, consists in the reduction of a metal, the cyanid of which is desired, concurrently with the production of nascent carbon in the presence of nitrogen, either free, or liberated from fluid compounds containing nitrogen in the process, whereby the nascent metal, nascent carbon and nitrogen unite directly forming a cyanid, and I do not desire to confine myself to the employment of any particular or specific compound or compounds in producing the cyanid as set forth but reserve the right to employ any ingredients which may justly be considered to come within the scope of my invention as broadly hereinbefore set forth. 85

In carrying out this process it is sometimes found, especially when the larger percentage of the oxy-salt or compound of the metal, a cyanid of which is desired, has been converted into cyanid, that the heat causes a direct dissociation of a portion of the petroleum or hydrocarbon into particles of free carbon and hydrogen gas which particles of free carbon remain suspended in and disseminated throughout the molten cyanid thereby temporarily contaminating the same. After all the oxy-salt or compound has been transformed into cyanid I remove these contaminating particles of free carbon by passing into or through the molten mass a current of oxygen or ordinary air whereby a portion of the metallic cyanid becomes converted into cyanate which, in turn, is reduced to cyanid by combination of the oxygen thereof with the free particles of carbon, thereby forming and eliminating carbonic acid and leaving the cyanid in a pure and uncontaminated condition. Care must be taken, however, that an excess of oxygen is not introduced, otherwise more carbon or other deoxidizing agent, such as hydrogen, would have to be supplied in order to finally remove the same and reduce it again to cyanid. I find it of advantage, however, to introduce into molten cyanid containing suspended particles of carbon, the percentage of which has previously been ascertained, a quantity of cyanate containing oxygen enough in proportion to the free carbon content to remove the same in the form of carbonic acid, by which means the excess of either free carbon or oxygen in the form of cyanate is avoided and the direct formation of cyanate for the removal of the particles of carbon within the cyanid is dispensed with. 100 110 115 120 125 130

The term "inert to cyanid" employed herein is intended to imply and does imply that the substance is not decomposed, transformed, or otherwise injuriously acted upon by the metal cyanid desired, nor is the cyanid which is desired decomposed, transformed, or otherwise injuriously acted upon by the oxygen-containing compound of the metal a cyanid of which is desired, whereby either or 5 both of the essential constituents viz. the oxygen-containing compound a cyanid of which is desired, the carbid transforming agent, or the metal cyanid desired are destroyed or injured by association.

15 The term "reacting temperature" employed throughout the specification and claims has reference to the temperature at which the electro-positive element of the carbid has an affinity for the oxygen of the 20 oxy-compound of the metal, the cyanid of which is desired, to the exclusion of carbon and which temperature is below that at which carbon will deoxidize an oxid of the electro-positive element or base of the carbid 25 employed, and the term "a gaseous body containing nitrogen" refers to nitrogen gas *per se* or gaseous mixtures of nitrogen or nitrogen yielding compounds.

Having now described my invention, what 30 I claim as new and desire to secure by Letters Patent is:—

1. The process of making cyanid which consists in exposing an oxy-compound of a metal inert to cyanid, the cyanid of which is 35 desired, to the action of a carbid at a temperature at which the electro-positive base of the carbid has greater affinity than carbon for the oxygen of the oxy-compound, and nitrogen.

40 2. The process of making cyanid which consists in exposing an oxy-compound of a metal inert to cyanid, the cyanid of which is desired, to the action of a carbid of a more electro-positive metal at a temperature at 45 which the electro-positive element or base of the carbid has greater affinity than carbon for the oxygen of the oxy-compound, and nitrogen.

3. The process of making cyanid which 50 consists in exposing a molten or liquefied oxy-compound of a metal inert to cyanid, the cyanid of which is desired, to the action of a carbid at a temperature at which the electro-positive base of the carbid has greater affinity than carbon for the oxygen of the oxy-compound, and nitrogen.

4. The process of making cyanid which 55 consists in exposing a molten material containing an oxy-compound of a metal inert to cyanid, the cyanid of which is desired, to the action of a carbid at a temperature at which the electro-positive base of the carbid has greater affinity than carbon for the oxygen of the oxy-compound, and nitrogen.

60 5. The process of making cyanid which

consists in exposing a molten composition containing an oxy-compound of a metal or metals inert to cyanid, the cyanid of which is desired, to the action of a metallic carbid at a temperature at which the electro-positive element or base of the carbid has greater affinity than carbon for the oxygen of the oxy-compound, and nitrogen.

6. The process of making cyanid which 70 consists in exposing a molten or liquefied oxy-compound of a metal inert to cyanid, the cyanid of which is desired, to the action of a gaseous carbid at a temperature at which the electro-positive element or base of the carbid has greater affinity than carbon for 75 the oxygen of the oxy-compound, and nitrogen.

7. The process of making cyanid which 80 consists in exposing an oxy-compound of a metal inert to cyanid, the cyanid of which is desired, to the action of hydrogen carbid at a temperature at which the hydrogen of the carbid has greater affinity than carbon for the oxygen of the oxy-compound, and nitrogen.

8. The process of making cyanid which 85 consists in deoxidizing, at a reacting temperature, by the action of a reducing agent having, at said reacting temperature, a greater affinity for oxygen than carbon, in the presence of nitrogen and nascent carbon, an oxy-compound of a metal inert to cyanid, the cyanid of which is desired.

9. The process of making cyanid which 90 consists in producing nascent metal, the 100 cyanid of which is desired, and nascent carbon, in the presence of nitrogen, by concurrently combining the electro-negative element of the compound of the metal inert to cyanid, a cyanid of which is desired, with the 105 electro-positive constituent of the carbon compound, at a temperature below which the electro-negative constituent of the compound of the metal employed combines with carbon, thereby combining the metal, carbon, and 110 nitrogen and producing a cyanid.

10. The process of making cyanid which 115 consists in inducing a union at a reacting temperature between the oxygen of an oxy-compound of the metal inert to cyanid, a cyanid of which is desired, and the electro-positive base of a carbid, in the presence of nitrogen, and simultaneously combining the metal of the oxy-compound, the carbon of the carbid, and the nitrogen, thereby forming a cyanid.

11. The process of making cyanid which 120 consists in deoxidizing an oxy-compound of a metal inert to cyanid, the cyanid of which is desired, by the action of hydrogen at a 125 temperature at which hydrogen has greater affinity than carbon for the oxygen of the oxy-compound, and combining the nascent metal of the oxy compound with carbon and nitrogen.

12. The process of making cyanid which consists in exposing at a temperature at which hydrogen has greater affinity than carbon for oxygen of an oxy-compound of a metal inert to cyanid, the cyanid of which is desired, such oxy-compound, hydrocarbon, and nitrogen, whereby the metal, carbon and nitrogen contents of the composition are brought to a combining condition and caused to unite by the concurrent combination of the hydrogen of the hydrocarbon and the oxygen of the oxy-compound of the reacting ingredients. 70
13. The process of making cyanid which consists in deoxidizing a hydroxid of a metal inert to cyanid, the cyanid of which is desired, at a temperature at which the deoxidizing agent has greater affinity than carbon for the oxygen of the hydroxid, in the presence of nascent carbon and superheated nitrogen and combining the nascent metal, nascent carbon, and nitrogen contents of the composition. 80
14. The process of making cyanid which consists in exposing a molten composition containing an oxy-compound of the metal inert to cyanid, a cyanid of which is desired, to the action of petroleum at a temperature at which hydrogen has greater affinity than carbon for the oxygen of the oxy-compound, and nitrogen. 90
15. The process of making alkali-metal cyanid which consists in exposing an oxy-compound of the alkali-metal inert to cyanid, a cyanid of which is desired, to the action of a hydrocarbon at a temperature at which the hydrogen of the hydrocarbon has greater affinity than carbon for the oxygen of the oxy-compound, and nitrogen. 100
16. The process of making alkali-metal cyanid which consists in exposing oxids of alkali-metals to the action of hydrogen carbid at a temperature at which the hydrogen of the carbid has greater affinity than carbon for the oxygen of the oxy-compound, and nitrogen. 105
17. The process of making alkali-metal cyanid which consists in exposing a molten composition containing an alkali-metal and oxygen inert to cyanid to the action of hydrogen carbid at a temperature at which the hydrogen of the carbid has greater affinity than carbon for the oxygen of the oxy-compound, and nitrogen. 110
18. The process of making alkali-metal cyanid which consists in exposing a composition containing an alkali-metal oxid to the action of petroleum at a temperature at which the hydrogen content has greater affinity than carbon for the oxygen of the oxy-compound, and nitrogen. 120
19. The process of making alkali-metal cyanid which consists in exposing a hydroxid of the alkali-metal, a cyanid of which is desired, to the action of petroleum at a temperature at which the hydrogen content has greater affinity than carbon for the oxygen of the oxy-compound, and nitrogen. 125
20. The process of making potassium cyanid which consists in exposing a molten compound containing potassium and oxygen inert to cyanid to the action of hydrogen carbid at a temperature at which the hydrogen of the carbid has greater affinity than carbon for the oxygen of the oxy-compound, and nitrogen. 75
21. The process of making potassium cyanid which consists in fusing caustic potash and introducing into and through the same, hydrocarbon and nitrogen while the materials are heated to a temperature at which the hydrogen of the hydrocarbon has greater affinity than carbon for the oxygen of the caustic potash. 80
22. The process of making potassium cyanid which consists in exposing a molten composition containing potassium hydrogen oxid (hydroxid) to the action of petroleum and nitrogen at a temperature at which the hydrogen content of the petroleum has greater affinity than carbon for the oxygen content of the potassium hydroxid. 85
23. The process of making cyanids which consists in exposing an oxy-compound of a metal inert to cyanid, the cyanid of which is desired, to the action of a carbid, the electro-positive base of which is capable of uniting with the oxygen of the oxy-compound, and nitrogen, at a reacting temperature and finally removing any particles of free carbon contained therein by introducing into the mass an oxidizing agent capable of converting the cyanid into a cyanate in sufficient proportion to remove the contaminating carbon. 95
24. The process of making cyanids which consists in uniting a metal, the cyanid of which is desired, with carbon and nitrogen in proportion to form the same by subjecting ingredients containing said metal, carbon and nitrogen to mutual reaction at a combining temperature and removing any excess of carbon contained therein by the action of a metallic cyanate. 110
25. The process of making cyanids which consists in exposing an oxy-compound of a metal inert to cyanid, the cyanid of which is desired, to the action of a carbid of a more electro-positive element, in the presence of nitrogen and removing any excess of carbon contained therein by the action of a metallic cyanate. 115
26. The process of making cyanids which consists in exposing an oxy-compound of a metal inert to cyanid, the cyanid of which is desired, to the action of hydrocarbon and nitrogen at a reacting temperature, and removing any excess of carbon contained therein by the action of a metallic cyanate. 125
27. The process of making cyanid which 130

consists in exposing an oxy-compound of a metal inert to cyanid, the cyanid of which is desired, to the action of a carbid, the electro-positive element or base of which is capable 5 of uniting with the oxygen of the oxy-compound, at a temperature below that at which carbon will deoxidize an oxid of the electro-positive element or base of the carbid employed, and nitrogen.

10 28. The process of making cyanid which consists in exposing an oxy-compound of a metal inert to cyanid, the cyanid of which is desired, to the action of a carbid, the electro-positive element or base of which is capable 15 of uniting with the oxygen of the oxy-compound, at a temperature at which the electro-positive element of the carbid will deoxidize oxid of carbon, and nitrogen.

29. The process of making cyanid which 20 consists in deoxidizing an oxy-compound containing a metal inert to cyanid, the cyanid of which is desired, by a deoxidizing agent, contained in a carbonaceous compound, which has a greater affinity for the 25 oxygen of the oxy-compound than the carbon of the carbonaceous compound at the temperature employed, and combining the carbon of the deoxidizing compound, the metal of the oxy-compound and nitrogen 30 thereby forming a cyanid.

30. The process of making cyanid which consists in exposing an oxy-compound of a metal inert to cyanid, the cyanid of which is desired, to the action of a carbid at a temperature 35 at which the electro-positive element has an affinity for the oxygen of the oxy-compound to the exclusion of carbon, and a gaseous body containing nitrogen.

31. The process of making cyanid, which 40 consists in fusing an oxy-compound of a metal inert to cyanid, and introducing into and through the same a fluid deoxidizing oil and nitrogen, at a reacting temperature.

32. The process of making cyanid, which 45 consists in fusing an oxy-compound of a metal inert to cyanid, and introducing into

and through the same petroleum and nitrogen, at a reacting temperature.

33. The process of making cyanid, which consists in fusing an oxy-compound of an 50 alkali-metal inert to cyanid, and introducing into and through the same a fluid deoxidizing oil and nitrogen, at a reacting temperature.

34. The process of making cyanid, which consists in fusing an oxy-compound of an 55 alkali-metal inert to cyanid, and introducing into and through the same petroleum and nitrogen, at a reacting temperature.

35. The process of making potassium cyanid, which consists in fusing caustic potash, 60 and introducing into and through the same a fluid deoxidizing oil and nitrogen, at a reacting temperature.

36. The process of making potassium cyanid, which consists in fusing caustic potash 65 and introducing into and through the same petroleum and nitrogen, at a reacting temperature.

37. The process of making potassium cyanid, which consists in fusing caustic potash 70 or substance containing the same, and introducing into and through the fused substance hydrocarbon and nitrogen, at a reacting temperature.

38. The process of making cyanid, which 75 consists in exposing metal oxy-compounds inert to cyanid during process of deoxidation yielding nascent carbon to the action of super-heated nitrogen.

39. The process of making potassium cyanid, which consists in deoxidizing caustic potash with a deoxidant yielding nascent carbon, and exposing the ingredients during process of deoxidation to the action of super-heated nitrogen. 80 85

In testimony whereof I affix my signature, in presence of two witnesses.
